UNITED STATES PATENT OFFICE.

JOSEPH J. MIZER AND VICTOR JAKOB, OF RACINE, WISCONSIN, ASSIGNORS TO WALKER MANUFACTURING COMPANY, OF RACINE, WISCONSIN, A CORPORATION OF WISCONSIN.

DESIGN FOR A LIFTING-JACK.

54,442.

Specification for Design.

Patented Feb. 10, 1920.

Application filed August 30, 1919. Serial No. 320,952. Term of patent 14 years.

To all whom it may concern:

Be it known that we, JOSEPH J. MIZER, a citizen of the United States, and VICTOR JAKOB, a citizen of Germany, residing at Racine, in the county of Racine and State of Wisconsin, have invented a new, original, and ornamental Design for Lifting-Jacks, of which the following is a specification, reference being had to the accompanying drawing, forming part thereof, in which—

Figure 1 is a plan view of a lifting jack

showing our new design, the handle being broken off, and

Fig. 2 is a side elevational view of the lifting jack, certain portions of the handle being broken out.

We claim:

The ornamental design for a lifting jack as shown.

JOSEPH J. MIZER.
VICTOR JAKOB.
